UNITED STATES PATENT OFFICE.

JOSEPH TERNES, OF HENDERSON, KENTUCKY.

WARDROBE-BRACKET.

SPECIFICATION forming part of Letters Patent No. 752,128, dated February 16, 1904.

Application filed August 26, 1903. Serial No. 170,848. (No model.)

To all whom it may concern:

Be it known that I, JOSEPH TERNES, a citizen of the United States, residing at Henderson, in the county of Henderson and State of Kentucky, have invented a new and useful Wardrobe-Bracket, of which the following is a specification.

This invention relates to devices for suspending garments in wardrobes, closets, and the like; and it has for its object to provide a device of this class comprising a plurality of independent brackets individually foldable within a wardrobe, closet, or similar place of storage in such a manner that all of the garments thus supported shall be easily accessible and also in such a manner that all of the garments thus stored shall be kept smoothly, evenly, and free from unnecessary wrinkles.

With these and other ends in view my invention consists in the improved construction, arrangement, and combination of parts which will be hereinafter fully described, and particularly pointed out in the claims.

In the accompanying drawings, Figure 1 is a perspective view showing a wardrobe with the door open, said wardrobe being equipped with brackets of my invention. Fig. 2 is a horizontal sectional view showing the wardrobe closed. Fig. 3 is a perspective view illustrating a modification. Figs. 4 and 5 are detail views illustrating other modifications.

Corresponding parts in the several figures are indicated by similar numerals of reference.

In the accompanying drawings I have illustrated my invention as applied to a wardrobe, which is designated 1 and which is provided near the top thereof with a shelf 2. Said wardrobe is also provided with a hinged door 3.

In diagonally opposite corners of the wardrobe are pivotally mounted a pair of uprights 4 and 5, the latter of which is placed closely adjacent to the hinged edge of the door. The upper ends of these uprights are mounted pivotally in the under side of the shelf 2 and their lower ends either in the bottom of the wardrobe or in slats or blocks, such as 6, which have been provided for strengthening purposes. The upper ends of the uprights 4 and 5 are provided with laterally-extending

arms 7 8, which are connected in the example illustrated in the drawings by means of ornamental braces 9 with points about midway of the said uprights. The arms 7 and 8 are provided with garment-supporting hooks 10, which when the said arms are in the closed position shown in Fig. 2 are upon the adjacent sides or faces of said arms. Said hook members 10 are also disposed intercurrently upon the said arms in order to avoid interference with each other.

The garment-supporting arms 7 and 8 are connected by means of a pivoted link 11, the ends of which are pivotally connected with said arms near the outer ends of the latter. Upon the rear side of what may be termed the "outer" arm 8 is suitably secured a keeper 12, consisting of a wire having inturned ends which are suitably connected with the said arm 8 in such a manner as to sustain the said wire at a distance of about half an inch from the face of said arm. This keeper, which is of suitable length, is engaged by a hook member 14, which practically encircles the keeper, so as to ride upon the latter when the door is opened, the opening of the door thus serving to throw in an outward direction the arm 8, which latter, by means of the link 11, will simultaneously draw the arm 7 in an outward direction to the position illustrated in Fig. 1 of the drawings, thus practically exposing the entire contents of the wardrobe. When the door is closed, the bracket members will be automatically folded within the wardrobe, the rear member being folded against the rear wall, while the front member remains practically in contact with the front door, the garments suspended from the hooks 10 being thus closely packed within the wardrobe and in such a manner as to avoid mussing or wrinkling the same in the act of being packed.

In the modification of the device illustrated in Fig. 3 the bracket members of my invention are modified to this extent, that the lower ends of the uprights 4 and 5 instead of being extended to the floor of the wardrobe are swiveled in shelves or brackets 15, appropriately disposed in the wardrobe. In other respects the construction and operation are the same. This modification may be resorted

to when it is desired to reserve space in the bottom of the wardrobe.

My invention, as is obvious, may be applied to all kinds of closets and storage-places of a similar nature and in all cases with the same advantages and results. The brackets may be manufactured separately and applied to old wardrobes, closets, and the like, as well as to new ones, inasmuch as no alteration in the general construction of the storage-chamber is required. It will also be obvious that it is not necessary to provide a shelf for the pivotal arrangement of the upper ends of the uprights 4 and 5, inasmuch as the same may be pivoted directly in the top of the storage-place. It is also unnecessary that the arms 7 and 8 having the garment-supporting hooks should be disposed at the extreme upper ends of the uprights, inasmuch as they may with equally advantageous results be disposed upon the said uprights at any intermediate point or points. It is likewise obvious that more than a single arm having garment-supporting hooks may be applied to each upright, especially when the wardrobe, closet, or other storage-place is of considerable height or when the garments to be stored are not of very great length. I also desire it to be distinctly understood that the precise structure of my improved garment-supporting brackets which has been herein shown and described need not be adhered to. Thus, for instance, the uprights, arms, and supporting-brackets 9 might be manufactured of metal bent into suitable shape, as will be understood by reference to Fig. 4 of the drawings, or separate uprights might be provided and arms and brackets, as 7 and 9, might be formed from wire of suitable gage suitably bent and connected with the uprights, and in the latter case the garment-supporting hooks might be formed integrally with such wire, such a construction having been illustrated in Fig. 5 of the drawings.

Be it understood, therefore, that I do not limit myself with regard to structural details 45 of this device, but reserve to myself the right to any changes, alterations, and modifications which may be resorted to within the scope of my invention and without departing from the spirit or sacrificing the utility of the same. 50

Having thus described my invention, I claim—

1. In a storage-closet, a pair of diagonally opposite pivoted uprights having laterally-extending arms provided with garment-supporting hooks, a link pivotally connecting the free ends of said arms, a door mounted hingedly adjacent to the outer upright, and means supported by said door and having sliding connection with the arm of said outer upright.

2. The combination with a storage-closet, of a pair of diagonally opposite pivoted uprights, one of said uprights being disposed adjacent to the hinged edge of the door constituting the closure of such closet, said uprights having laterally-extending garment-supporting arms, a link connecting said arms, a keeper upon the arm adjacent to the door, and a hook member upon said door slidably engaging said keeper.

3. In a storage-closet, a pair of garment-supporting arms disposed opposite to each other and pivoted to the closet to swing upon diagonally opposite vertical axes, a link connecting said arms, and a slidable connection between one of said arms and a door, the latter having hinged connection with the closet.

In testimony that I claim the foregoing as my own I have hereto affixed my signature in the presence of two witnesses.

JOSEPH TERNES.
